CLAIM

The ornamental design for an arm chair, as shown and described.

DESCRIPTION

FIG. 1 is a generally perspective view of a preferred embodiment of the arm chair.

FIG. 2 is a front elevational view of FIG. 1.

FIG. 3 is a left hand side elevational view of FIG. 1.

FIG. 4 is a top plan view of FIG. 1.

FIG. 5 is a rear elevational view of FIG. 1.

FIG. 6 is a bottom plan view of FIG. 1.

The broken line showing of cushions in FIG. 3 is for environmental purposes only and forms no part of the claimed design.

FIGS. 2 through 6 have been shown on an enlarged scale with respect to FIG. 1.
